INVENTOR.

Nellie Lewis,
By Carl P. Fockel
Attorney.

UNITED STATES PATENT OFFICE.

NELLIE LEWIS, OF BROOKLYN, NEW YORK.

COLLAR-BAND FOR SHIRTS.

1,370,600.

Specification of Letters Patent.

Patented Mar. 8, 1921.

Application filed May 16, 1918. Serial No. 234,980.

To all whom it may concern:

Be it known that I, NELLIE LEWIS, a citizen of Russia, and resident of the borough of Brooklyn, in the county of Kings and State of New York, have invented certain new and useful Improvements in Collar-Bands for Shirts, of which the following is a specification.

The present invention relates to an improved collar band for shirts, and more particularly the present improvements consist in providing permanent collar buttons in connection with the shirt band.

With the present type of shirt bands and detachable collar buttons in use, the wearer is subjected to much inconvenience and annoyance. Principally because of the necessity of having to continually remove and insert the collar buttons, and through accidents or neglect, these collar buttons very often become lost, are not removed from the shirt when the same is sent to the laundry, and where new collar buttons are not always available, the wearer is put to considerable inconvenience. Also the collar button holes in the shirt very soon become enlarged, and as a result, the collar button can not be properly retained in the shirt, either slipping to such extent as to change the position of the collar, or else coming out of the button hole.

Furthermore the backs of the collar buttons are exposed, and in contact with the neck of the wearer, which is both uncomfortable and dangerous, because of the danger of blood poisoning.

It is an object of the present invention therefore to provide a shirt band having permanent collar buttons, attached in such manner that they will not become changed in their position, may be conveniently set in place, and will not prove an inconvenience in laundering the shirt.

It is a further object to provide an improved construction of shirt band in connection with the collar button, which will prevent the metal of the collar button from touching the neck, and will hold the collar button always in upright position so that the collar will be retained properly upon the neck band.

With these and other objects in view, an embodiment of my invention is shown in the accompanying drawings, and this embodiment will be hereinafter more fully de-

scribed with reference thereto, and the invention will be finally pointed out in the claims.

In the accompanying drawings;

Figure 1 is a perspective view of a collar band embodying my improvements;

Fig. 2 is an elevation of the collar button employed;

Fig. 3 is a plan view thereof;

Fig. 4 is an elevation partly in section showing the ball head removed;

Fig. 5 is a plan view of a portion of the front layer of the shirt band showing a button hole worked therein;

Fig. 6 is a sectional view taken along the line 6-6 of Fig. 5, showing the collar button in place, and with the head removed;

Fig. 7 is a plan view showing the front and back layers of the collar band attached, and with the collar button in place;

Fig. 8 is a sectional view along the line 8-8 of Fig. 7;

Fig. 9 is a plan view showing the collar band attached to a portion of the shirt;

Fig. 10 is a sectional view along the line 10-10 of Fig. 9, and

Fig. 11 is a sectional view of the front and back layers as first attached with the raw edges exposed.

Similar reference characters indicate corresponding parts throughout the several figures of the drawings.

Referring to the drawings, the collar band constructed according to the present embodiment of my invention comprises a front layer of material 10 folded longitudinally upon itself to form an inner layer 11, a marginal portion 12 being folded over upon the layer 11. A small circular button hole or eyelet 13 is worked at the point where it is desired to place a collar button, this button hole extending through both thicknesses of the front layer, and being substantially reinforced by button hole stitching 14.

The collar button comprises a base 15, slightly greater than a semi-circle, a stem 100 or shank 16 extending from the circumferential center of the base and provided at its upper end with a detachable head 17, the said head being preferably provided with a threaded extension 18, which engages the threaded bore 19 of the stem, although other suitable means of attachment may be provided.

While I have shown the head as ball shape, it will be understood that the back collar button may have a short shank and a flat head.

5 In assembling the collar band and collar button, the head 17 is removed from the button, and the stem is inserted in the eyelet 18, the base 15 engaging the inner side 11 of the front layer of the collar band, 0 and having its straight edge 20 parallel with the lower edge of the collar band.

The rear layer of the collar band is substantially the same in form as the front layer, and comprises an outer fold 22 and 15 an inner fold 23, and a turned over marginal portion 24. This layer is placed upon the front layer with the folds 12 and 24 straightened out and with the edges of the two layers conforming (Fig. 11) and 20 cured together by a row of stitching 25^a. The portions 10, 11 and 22, 23, are then folded down upon the folds 12 and 24 the ends being held by the stitches 25^a and a single row of stitching 25 is stitched through 25 the portions 10, 11, 12 and 22, 23, 24, above the stitches 25^a inclosing the folds 12 and 24. Another single longitudinal row of stitching 26 is provided spaced from and parallel with the lower edges of the front 30 and rear layers of the collar band, and directly beneath the straight edge 20 of the base of the collar button, thus forming a fold at the lower edge of the collar band within which the edge of the shirt may be 35 inserted, and at the same time preventing rotation of the collar button. Preferably an arcuate row of stitching 27 is placed about the circumferential portion of the base 40 of the collar button, this row of stitching passing entirely through the shirt band, as clearly indicated in Fig. 8.

With the exception of the slightly different form of the rear collar button, which is preferably flat, the construction of the shirt band at that portion surrounding the rear collar button, is the same as that surrounding the front collar button. The front ends of the shirt band are finished in the usual manner as at 28 and 29, and a button 50 hole 30 is provided in the end of the shirt band opposed to that containing the collar button, and is adapted to engage the collar button.

The band is attached to the neck of the 55 shirt by inserting the edge 31 of the shirt into the fold formed between the front and rear layers of the band, and securing it by

a row of stitching 32, as clearly indicated in Figs. 9 and 10.

With my improvements, it will be seen, 60 a shirt band is provided having permanent and immovable collar buttons, the stems of which are always maintained in upright position, thereby preventing pressure upon the neck, and the construction of the rear 65 layer of the shirt band forms a protective pad which prevents contact of the collar button with the neck. The invention may, if desired, be used in connection with other garments as for instance military garments. 70

The collar buttons may be formed of any suitable material, such for instance as bone, aluminum, gold, silver, etc., and are preferably of a material which will not be affected by moisture. 75

I have illustrated a preferred and satisfactory embodiment of my invention, but it is obvious that changes may be made therein within the spirit and scope thereof, as defined in the appended claims. 80

I claim:—

1. The combination with a collar band comprising an inner and an outer layer joined above the neck band by a line of stitching, the outer layer having an eyelet, adapted to receive a collar button having a base with a straight edge portion contiguous to the stitching and prevented from rotating by abutting against the stitching, a shank of a diameter substantially 85 the same diameter as that of the eyelet of the outer layer and extending through the eyelet of the outer layer, and a removable head for the shank.

2. The combination with a collar band 95 comprising an inner and an outer layer joined above the neck band by a line of stitching, the outer layer having an eyelet, adapted to receive a collar button having a base with a straight edge portion contiguous to the stitching, a line of stitching 100 extending about the remainder of the periphery of said base, said base being prevented from rotating by its straight edge abutting against the said line of stitching 105 joining the said layers to the neck band, a shank of a diameter substantially the same as the diameter of the eyelet of the outer layer and extending through the eyelet of the outer layer, and a removable head 110 for the shank.

In testimony that I claim the foregoing as my invention I have signed my name.

NEILIE LEWIS.
